UNITED STATES PATENT OFFICE.

WILLIAM S. SHERD, OF CASTLE ROCK, MINNESOTA.

DRIVING-REIN.

SPECIFICATION forming part of Letters Patent No. 268,046, dated November 28, 1882.

Application filed July 31, 1882. (No model.)

To all whom it may concern:

Be it known that I, WM. S. SHERD, a citizen of the United States, residing at Castle Rock, in the county of Dakota and State of Minnesota, have made new and useful Improvements 5 in Driving-Reins, of which the following is a specification.

The invention relates to driving-reins; and it consists in the construction and arrangement of parts substantially as hereinafter specifically described and claimed.

In the drawings, Figure 1 is an outline diagram of a team of horses, viewed from above, showing the reins in position and my improvement attached thereto. Fig. 2 is a front view, and Fig. 3 is a side view, about full size, of the swivels detached. Fig. 4 is a view of one of the swivels detached and the parts disconnected.

Much annoyance and trouble are generally experienced in harnessing and driving horses by the reins becoming twisted. This is especially true where two or more horses are driven together; and to prevent the reins becoming twisted is the object of my invention, which consists in arranging in the circuit of the reins where the leading-reins are connected to the main guiding-reins small metal swivels, so that no matter how much the reins may be 25 twisted when the horses are harnessed the swivels will permit them to readily untwist of 30 their own accord.

In the drawings, A' A² represent the outer leading-reins, and B' B² represent the inner leading-reins, each attached at one end to the bits of the horses, and at the other end each usually attached by buckles c' c² to the main driving-reins D' D²; but in my device I insert 35 small metal swivels between the buckles c' c²

and the leading-reins A' A² B' B², as shown. 40 These swivels consist of two metal rings or eyes, E' E², one eye having a pin, a, (see Fig. 4,) fitting through a hole in the other eye, and secured therein by being riveted in a head or washer, b, or secured in any other suitable 45 manner to enable one eye to swing freely around the other. The ends of the driving-reins are secured in one pair of these eyes and the ends of the leading-reins secured in the other eyes in the ordinary manner by sewing or riveting. 50 The leading-reins are usually formed of round straps, while the driving-reins are usually formed of flat straps, although they may be made in any desired form. By this simple arrangement the reins cannot become twisted, 55 as the swivels will enable the natural torsional strain of the leather to untwist them when twisted. Hence no time need be occupied in straightening and untwisting the reins in harnessing, as they will untwist of themselves, no 60 matter how badly twisted.

I have only shown the swivels applied to a double harness, to which they are especially applicable; but they may be also used on single harness, if desired. 65

I claim as my invention—

The combination of the leading-reins A' A² B' B², driving-reins D' D², and swivels E' E², arranged and operating substantially as set forth. 70

In testimony whereof I have hereunto set my hand in the presence of two subscribing witnesses.

WM. STEPHEN SHERD.
